Primary Examiner — Sandra Snapp*Assistant Examiner* — Mehri Bajoul(57) **CLAIM**

The ornamental design for a portable soccer goal, as shown and described.

DESCRIPTION

FIG. 1 is a perspective view of a portable soccer goal showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another perspective view thereof, showing some pins with broken lines for mounting the portable soccer goal. The broken lines depict environment only and form no part of the claimed design.

1 Claim, 8 Drawing Sheets(56)
